UNITED STATES PATENT OFFICE.

EDWARD POHL, OF PATERSON, NEW JERSEY.

APPARATUS FOR LUSTERING AND FINISHING SILK FILAMENTS.

No. 808,402.

Specification of Letters Patent.

Patented Dec. 26, 1905.

Application filed April 13, 1905. Serial No. 255,352.

To all whom it may concern.

Be it known that I, EDWARD POHL, a subject of the Emperor of Austria-Hungary, and a resident of Paterson, county of Passaic, State 5 of New Jersey, have invented certain new and useful Improvements in Apparatus for Lustering and Finishing Silk Filaments, of which the following is a specification, reference being had to the accompanying drawings, forming 10 a part thereof.

In apparatus of the class to which this invention relates means are provided for immersing silk filaments in a bath containing a suitable liquid and for drying and lustering 15 the filaments by carrying them from the bath over a heated surface. Certain means is provided for removing the surplus moisture from the filaments as they come from the bath and for initially drying same; but 20 the final drying takes place during the time the filaments pass over the heated surface. In operating machines of this character I have found that a considerable quantity of solution from the filaments becomes deposited upon 25 the approach end of the heated surface, where it cakes and dries, thereby seriously interfering with the efficiency of the apparatus and tending to injure the filaments by dirtying them. To stop the apparatus for the purpose 30 of frequently cleansing this surface entails a waste of time and consequent loss; and it is the main object of this invention to provide such means as will prevent the lodgment of this material on the heated surface.

To these ends my invention consists in the provision of a heated body having a plurality of contact-surfaces over any one of which the filaments may pass, said heated body located between the bath and the aforesaid main heated 35 surface and held stationary during the normal operation of the machine. The filaments are arranged to pass from the bath over any one of the contact-surfaces of the said heated body before passing to the main 40 heated surface, and the said body is provided with means whereby it may be caused to present its several surfaces successively, as may be desired, whereby as one surface becomes dirty another clean surface may be brought 45 into use.

I will now describe an apparatus embodying my invention and will then point out the novel features in claims.

In the drawings, Figure 1 is a view in central vertical longitudinal section of an apparatus embodying my invention. Fig. 2 is an

enlarged view, partly in plan and partly in horizontal section, showing the movable heated body and contiguous parts. Fig. 3 is a detail sectional view, on an enlarged scale, of the 60 same.

In the device herein illustrated a bath 1 contains the required liquid, through which silk filaments 2 are drawn. The filaments then pass over a sponge 3, arranged in a perforated trough 4, and over a felt pad 5, suitably supported, whereby superfluous liquid carried up by the filaments may be returned to the bath or suitably absorbed. The filaments pass from the felt pad 5 over a heated 65 absorber 6, comprising a perforated steam-pipe 7, suitably covered with felt 8 or other absorbent material, and will finally pass to the heated flat surface, (designated as a whole by the reference character 9,) such heated surface being conveniently the top of a steam-table 10. The steam-table is heated by means of steam-pipes comprising headers 11 and connecting-pipes 12. Pipe connections 18 are shown as leading from the front header 70 to the pipe 7 for the purpose of conveying steam to the latter, steam being admitted from a suitable source of supply 13 to the front header 11 and exhausted through a pipe 14 from the rear header. The approach 75 portion of the steam-table is preferably arranged as a separate and removable portion 15, the same being suitably secured in position and readily removable when desired for cleaning purposes. 80

I make no claim herein to the above features comprising the absorber 6 or the removable member 15 of the steam-table 10, as the same form part of the subject-matter of a separate copending application filed October 95 14, 1905, and serially numbered 282,703.

Intermediate the bath 1 and the approach end of the steam-table 10 I have provided a member 16, revolubly mounted upon trunnions 17, comprising branches from the steam-pipes 18. This member 16 is polygonal in cross-section, being provided with a plurality of flat sides arranged at equal distances from its axis of rotation. By reason of this and of the fact that the member is revoluble successive sides may be presented for engagement with the filaments, as is desired. Thus as one contact-surface becomes dirty a fresh contact-surface may be brought into use, it being understood that the said member 16 is 105 held stationary during the normal operation of the machine. The member 16 is hollow, 110

and steam is admitted thereto from pipes 18 for the purpose of heating same. The filaments in passing from the bath will pass over one of the surfaces of the member 16 before 5 passing to the steam-table, and the said surface of the member 16 will thus receive and remove as much as possible of the surplus material carried by the filaments before the filaments pass to the steam-table. As one surface 10 of the member 16 becomes caked or fouled another surface may be brought into play by partially rotating the member, and this without stopping the machine. Thus the surface of the steam-table 10 will largely be 15 prevented from being fouled, so as to permit the practically continuous use of the machine.

The relative location of the members 6 and 16 may be varied so long as the latter member 20 is retained in its position intermediate the bath and the steam-table.

The amount of work performed in an apparatus constructed in accordance with my invention is not only increased by reason of the 25 time saved due to the practically continuous operation of the machine, but the quality of the work is improved, because the lustering which is effected by the heated surface takes place upon a surface which is always clean. 30 In former machines this surface was often permitted to become quite foul in order to

avoid the loss of time necessary in stopping the machine to clean same. In the present machine the surfaces of the heated body 16 not in use may be readily cleaned, so that 35 such surfaces will again be ready for successive employment without it being necessary to stop the machine even after all the surfaces provided have been successively employed.

What I claim is—

1. In a machine for finishing and lustering textile filaments, the combination with a bath for containing liquid in which the filaments are to be immersed, of a heated body polygonal in cross-section, the surfaces of which 45 constitute contact-surfaces arranged to be successively employed, said heated body being stationary during the normal operation of the device.

2. In a machine for finishing and lustering 50 textile filaments, the combination with a bath for containing liquid in which the filaments are to be immersed, and a heated contact-surface over which the filaments are arranged to travel, of a heated body having a plurality 55 of contact-surfaces arranged to be successively employed, said heated body arranged between the bath and the aforesaid contact-surface.

EDWARD POHL.
